HENRY P. PINKHAM, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH AND FABRICATED FRAMES THEREFOR

Application filed April 2, 1930. Serial No. 440,942.

This invention relates to oil immersed electric switches and to the oil containing enclosing casing therefor.

In the usual high tension electric switch the switch members are separated under a body of oil which is enclosed in a casing that comprises an open top oil receptacle and a switch frame that constitutes a cover for the open top of the receptacle and provides a rigid support for the switch members and the switch operating mechanism. Heretofore the oil receptacle has been made of sheet metal preferably of sheet steel and the switch frame has been made as a casting, usually of cast iron, although for large switches cast steel has been employed. When the switch is opened under heavy load, considerable gas is evolved at the switch contacts under the oil and oil is thrown violently up against the cover and thus is thrown outside the switch through any openings or open joints that may be present in the casing. Such throwing of oil is highly undesirable. Thus with the usual switch construction the confronting surfaces of the oil receptacle and the switch frame have been machined to provide plane contacting surfaces in an attempt to provide oil tight joints therebetween. Inasmuch as the casting comprising the switch frame has a strong tendency to warp after it has been machined it is exceedingly difficult to maintain the joint tight as the machined surface will become warped and distorted. Thus, it will leave open passages through which the oil can be expelled. Furthermore, when large production and speedy deliveries are involved the cast switch frame becomes an expensive proposition due to the fact that much machine work is necessary, involving the use of skilled labor, irregular shapes have to be machined, and a considerable number of machined switch frames have to be rejected as defective by reason of being warped and for numerous other reasons. Furthermore, a cast switch frame when subjected to strong internal pressures is liable to burst, instead of merely yielding under the pressure, and thereby renders the switch useless. Consequently an object of the pres-

ent invention is the provision of an oil immersed switch having a switch frame which is so constructed that it has surfaces that can be made practically oil tight without being machined, that has practically no tendency to warp and thereby distort such surfaces, that is adapted to yield instead of burst when subjected to unusually high pressures, and that can be made at considerably less cost than a cast switch frame.

In addition to the above enumerated defects a cast switch frame frequently has pores which are hard to detect without elaborate and expensive tests. The presence of pores is highly objectionable, especially in a switch of the outdoor type, since they leak water into the interior of the switch and thereby reduce the dielectric strength and arc-interrupting properties of the oil and thus seriously impair the effective operation of the switch and may cause it to fail under small loads.

A further object of the invention is the provision of a switch frame that is made from dense or pore-free metal and especially rolled and pressed metal wherein the various parts constituting the switch frame are welded together into an integral unit.

A further object of the invention is the provision of a switch frame having a dome which is formed of pressed metal, an outstanding supporting flange of sheet metal at the base of the dome and which is welded thereto, and a depending receptacle-enclosing apron also of sheet metal which is disposed under and is welded to the flange. A switch frame thus constructed is superior to a cast metal switch frame in many respects. It is cheaper to make. The dimensions of duplicate switch frames are practically identical since the parts are shaped and formed in the same dies whereas two cast switch frames made from the same pattern will vary largely in dimensions due to variable shrinking of the cast metal and to variable treatment of the pattern when making the sand mould. The rolled plates provide smooth flat surfaces that do not require machining to provide oil tight joints. The rolled plate from which the parts are

made has a fibrous structure instead of a crystalline structure as with cast metal and so will yield and stretch when subjected to unusual internal pressures instead of bursting as will a cast switch frame.

5 A further object of the invention is generally to improve the construction and operation of electric switches.

10 Fig. 1 is a side elevation of an electric switch embodying the invention.

15 Fig. 2 is a plan view of the switch top of the invention.

20 Fig. 3 is a longitudinal sectional elevation of Fig. 2.

25 Fig. 4 is a plan view of the base plate.

30 Fig. 5 is a sectional detail taken along line 5—5 Fig. 2.

35 As herein shown, the switch embodying the invention includes a switch frame, or top, 10 which is adapted to receive therewithin and provide a cover for the open top of an oil receptacle 12 which herein is elliptical. The switch frame 10 provides a support for a pair of stationary switch members including the insulating bushings 14 and the central conducting studs 16 which extend through the top wall of said switch frame and depend therebelow into said oil receptacle 12 and which are provided at their lower ends with the usual stationary contact members, not shown. Said switch frame further provides an upper mechanism compartment within which is enclosed the switch operating mechanism for reciprocating the usual movable switch member, not shown, into and out of engagement with the fixed contact members to close and open the circuit through the switch.

40 The switch frame 10, with which this invention is particularly concerned, includes a top or dome 18, an outstanding supporting plate or flange 20, and a depending apron 22, all of which are formed of relatively thick rolled sheet metal, preferably 45 steel.

50 The dome 18 is formed from a flat plate, preferably boiler plate, and is pressed between dies into the shape shown, which provides an upstanding side wall 24 which bounds an elliptical area, and a top consisting of two flat sections 26 which are inclined slightly upward and meet at the ridge 28 which extends transversely across the middle of the dome. The flat sections each 55 have a circular hole 30 punched therethrough, preferably after pressing the sheet into dome-shape, to admit a switch terminal bushing 14. Drilled and tapped holes 32 are subsequently formed in the sections, 60 around said bushing-holes, to receive bolts 34 which secure the flanges 36 of the bushings against the flat outer faces of the sections. The pressing operation provides the sections with outer faces which are sufficiently plane and true to provide oil tight 65

joints between the sections and the flanges without the necessity for machining the faces when the usual paper or other packing discs 38 are located under the flanges.

70 A hole 40 is formed in the ridge 28 to admit a tool for adjusting the elevation of the movable switch member and said hole is closed by a pressed metal plate 42 which has angularly related sides that straddle the ridge and is welded or is otherwise secured thereto and has an opening 44 which registers with an upstanding pipe nipple 46 welded to the plate and closed by the removable cap 48. The plate also carries depending rods 50 which extend through holes 80 in the ridge and constitute guides for the movable switch member, not shown.

85 The flange 20 is formed of a flat steel plate and preferably is of rectangular shape and has an elliptical opening 51 in the middle thereof which is smaller than the open end of the dome and also of the oil receptacle. The bottom edge of the dome is seated on the top of the flange and is equally spaced from the opening 51 so that the flange provides an inwardly directed horizontal shelf 52 that is continuous around the inner periphery of the dome. The dome and the flange are integrally united by welding by either arc or gas flame, the welding material 54 being applied preferably around the junction between the outer surfaces of the dome flange.

90 The flange 20 also outstands beyond the outer surface of the dome and upstanding gusset plates 56 of triangular shape are welded to the opposite outstanding ends of the flange and to the upstanding wall of the dome to provide additional rigidity to the plate thereat since the switch usually 95 is supported on frame members 58 which engage the underside of the flange under said gusset plates.

100 The apron 22 is formed from a steel plate and is rolled or shaped into endless elliptical form and is located against the under face of the flange 20 in line with the upstanding side wall of the dome and is welded to the flange, thus being made integral with the flange and dome. Triangular 105 gusset plates 60 are welded to the outer faces of the flange and apron for strengthening both at the points where the bolts 62, which attach the oil receptacle to the switch frame, pass through the flange. The apron surrounds the side wall of the oil receptacle at the open top thereof and provides a support therefor which prevents the side wall thereat from being bulged outwardly by an unusually high pressure within 110 the casing.

115 The receptacle 12 is provided with an internal channel 64 at the top in which a packing 66 is received which engages the inwardly directed shelf 52 of the flange to 120

provide an oil tight seal between the oil receptacle and the flange. Since the flange is formed from a flat rolled sheet, the lower face thereof is sufficiently true to provide 5 a tight joint with the packing without being machined.

Various accessory parts are also welded onto the switch frame. Bosses 68 are welded onto the inner faces of the flat sections 10 of the dome, around the bushing-openings therethrough, to provide attaching means for current transformers, not shown, which surround the bushings, when such are used. The switch operating mechanism includes a 15 straight operating shaft 70, one end of which is shown in Fig. 1, and which extends entirely through openings in the opposite faces of the upstanding wall of the dome. Bearing blocks 72 for the shaft are located 20 within the dome and rest upon the shelf 52 of the frame and are welded thereto and to the dome. Weather-protecting casings 74 for the ends of the shaft, comprising the tubular necks 76 and outer outstanding 25 flanges 78 have their necks welded to the outer faces of the upstanding side wall of the dome. Pipe nipples 80 are welded onto the upstanding side wall of the dome to provide passages through which the leads 30 of the current transformers are extended. An elbow 82 is also welded to the side wall to provide a convenient means for filling the switch with oil or for venting the switch.

The switch frame thus constructed is 35 strong and rigid and is free from large surfaces that have to be machined and thus is considerably cheaper to make, especially in large quantities, than a cast metal frame.

While the invention is particularly effective in connection with the elliptical type 40 of switch frame here shown, as elliptical surfaces are considerably more difficult to machine than circular or rectangular surfaces, the invention is also effective for other shapes.

The switch frame construction here 45 shown is also shown and described in my co-pending application Serial No. 450,463, filed May 7, 1930.

I claim:

1. A fabricated top-frame for electric switches comprising an inverted terminal-supporting dome having a side wall which surrounds an open bottom, a plate under 55 said dome against the end of said side wall and having an opening therein within and conforming in general to the contour of said side wall and having bracket-constituting portions that extend outwardly beyond said side wall, and means securing said dome and plate together.

2. A fabricated top-frame for electric 60 switches comprising an inverted terminal-supporting dome having a side wall which surrounds an open bottom, a plate under said

dome against the end of said side wall and having an opening therein within and conforming in general to the contour of said side wall and having bracket-constituting portions that extend outwardly beyond said side wall, a tank-encircling flange located beneath said dome and plate and seated on the latter and encircling the opening in the plate, and means securing said dome, plate and flange together. 70

3. A fabricated top-frame for electric switches comprising an inverted terminal-supporting dome having a side wall which surrounds an open bottom, a plate under 75 said dome against the end of said side wall having an opening therein within and conforming in general to the contour of said side wall and having bracket-constituting portions that extend outwardly beyond said side wall, a tank-encircling flange located beneath said dome and plate and seated on the latter and encircling and spaced beyond the opening in the plate, and means securing said dome, plate and flange together. 80

4. A fabricated top-frame for electric switches comprising an inverted terminal-supporting dome having a side wall which surrounds an open bottom, a plate under 85 said dome against the end of said side wall and having an opening therein which is spaced a substantial distance from and conforms in general to the contour of said side wall, whereby to constitute a continuous tank-seat within the boundary of said dome, said plate having bracket-constituting portions that extend outwardly beyond said side wall, and means securing said dome and plate together. 90

5. A fabricated top-frame for electric switches comprising an inverted terminal-supporting dome having a side wall which surrounds an open bottom, a plate under 95 said dome against the end of said side wall and having an opening therein which is spaced a substantial distance from and conforms in general to the contour of said side wall, whereby to constitute a continuous tank-seat within the boundary of said dome, said plate having bracket-constituting portions that extend outwardly beyond said side wall, a tank-encircling flange located beneath said dome and plate and seated on the latter and spaced from and encircling said plate-opening, and means securing said dome, plate, and flange together. 100

6. A fabricated top-frame for electric switches comprising an inverted terminal-supporting dome having a side wall which surrounds an open bottom, a plate under 105 said dome against the end of said side wall and having an opening therein which is spaced a substantial distance from and conforms in general to the contour of said side wall, whereby to constitute a continuous tank-seat within the boundary of said dome, said plate having bracket-constituting portions that extend outwardly beyond said side wall, a tank-encircling flange located beneath said dome and plate and seated on the latter and spaced from and encircling said plate-opening, and means securing said dome, plate, and flange together. 110

115

120

125

130

said plate having bracket-constituting portions that extend outwardly beyond said side wall, a tank-encircling flange located beneath said dome and plate and seated on the latter and spaced from and encircling said plate-opening, means securing said dome, plate and flange together, and shaft-bearing blocks seated on and secured to the upper face of said tank-seat on opposite sides of said opening.

In testimony whereof, I have signed my name to this specification.

HENRY P. PINKHAM.
